[57] CLAIM

The ornamental design for a collar for an electric candle, as shown and described.

DESCRIPTION

FIG. 1 is a perspective view of a collar for an electric candle showing my new design;

FIG. 2 is a top plan view thereof;

FIG. 3 is a bottom plan view thereof;

FIG. 4 is a side elevational view thereof, the opposite side being a mirror image; and

FIG. 5 is a perspective view thereof on a reduced scale, the electric candle being shown in broken lines for illustrative purposes only.

FIG. 1

FIG. 2

FIG. 3

FIG. 5

FIG. 4
